LINE HOLDER

Humbert R. Rogant, Willoughby, Ohio

Application April 24, 1950, Serial No. 9,434

Term of patent 14 years

(Cl. D54—11)

To all whom it may concern:

Be it known that I, Humbert R. Rogant, a citizen of the United States, residing in Willoughby, in the county of Lake and State of Ohio, have invented a new, original and ornamental Design for a Line Holder, of which the following is a specification, reference being had to the accompanying drawing, forming part thereof.

In the drawing:

I claim:

The ornamental design for a line holder, substantially as shown.

HUMBERT R. ROGANT.
